(57) **CLAIM**

The ornamental design for an electronic console, as shown and described.

DESCRIPTION

FIG. 1 is an isometric view of an electronic console showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the encircled portion labeled as 8 in FIG. 6.

The even dash broken lines shown in the drawings illustrate portions of the electronic console that form no part of the claimed design; any unshaded regions between a solid and broken line forms no part thereof. The dash-dot broken lines showing enlarged views of encircled portions in FIGS. 6 and 8 are for annotative purposes only and form no part of the claimed design.
